(57) **CLAIM**

The ornamental design for an overhead interior console for a motor vehicle as shown and described.

DESCRIPTION

FIG. 1 is a bottom isometric view of an overhead interior console for a motor vehicle showing my new design;

FIG. 2 is a front isometric view thereof;

FIG. 3 is a rear isometric view thereof;

FIG. 4 is a left side isometric view thereof;

FIG. 5 is a right side isometric view thereof;

FIG. 6 is a top isometric view thereof; and,

FIG. 7 is another bottom isometric view thereof.

The broken lines in the drawings illustrate portions of the overhead interior console for a motor vehicle that form no part of the claimed design.

1 Claim, 7 Drawing Sheets
